UNITED STATES PATENT OFFICE.

VINCENT WISNIEWSKI, OF BERLIN, GERMANY, ASSIGNOR TO LUFTSCHIFFSANTRIEB GESELLSCHAFT MIT BESCHRANKTER HAFTUNG, OF BERLIN, GERMANY, A CORPORATION OF GERMANY.

SHED FOR AIRSHIPS AND THE LIKE.

1,101,372.

Specification of Letters Patent.

Patented June 23, 1914.

Application filed April 21, 1913. Serial No. 762,747.

To all whom it may concern:

Be it known that I, VINCENT WISNIEWSKI, architect, a subject of the German Emperor, and resident of Berlin, Germany, have invented new and useful Improvements in Sheds for Airships and the like, of which the following is a specification.

The present invention relates to a shed for airships and the like, the said shed having a circular plan.

The object of the present invention is to facilitate the bringing in and taking out of the airships in any direction, according to that of the wind, without it being necessary to turn the whole shed.

The invention consists in that the shed is constructed in such a manner, that it is composed of a plurality of sections, which may be pushed one over the other, whereby the shed will be opened toward the sides and also above, and in thus opening the shed only a part of the whole load has to be moved. By such arrangement it is obtained, that on the said sections being thus displaced, large openings are created, through which the airships can be taken in or brought out, the airship being even by almost one half uncovered from above, so that when it has been suitably balanced, it can be readily run out of the shed. Furthermore, as only a part of the shed has to be moved, the said openings for the airships to run in or out may be quickly made in any required direction.

In the accompanying drawings a constructional form of shed according to the present invention is exemplified.

Figure 1 is a horizontal section through an airship shed according to the present invention. Fig. 2 is a vertical section on an enlarged scale. Fig. 3 is an end view of an airship truck. Fig. 4 is a side view of the same. Fig. 5 is an enlarged sectional detail view and illustrates the method of jointing the several segments on each other. Figs. 6 and 7 are vertical end and plan views, respectively, and illustrate a modified form of the invention.

In the center of the shed stands a tower-like iron structure *a*, on which rotate the movable girder-like structures *b* and *c*. At their other ends these girders *b* and *c* travel by means of wheels, rails and the like on a circular bedplate *A*. The one set of girders, *b* are of a larger diameter than the girders *c*

so that the girders *b* can be pushed over the girders *c*, as shown in Fig. 2. The girders may be moved by different means, and it is obvious, that in the arrangement shown in the drawing, each girder may be pushed so far under or over its neighbor, that an opening is created. Furthermore, also one half of all girders may be pushed over the other half, so that one half of the shed will be completely uncovered and opened.

The airships are moved within the shed by aid of turntable carriages. The central towerlike structure contains a staircase and elevators, and a reflector at the top. With the object of keeping the center of the shed clear, two opposite sections of the smaller diameter may be connected by a suitable structure, on the fulcrum of which then the other girders or sections are made to rotate. The airships may either stand on the said turntable carriages (see Fig. 2, on the left) or they may also be suspended (see Fig. 2 on the right). The trucks *W*, which are fitted with turntables, (Figs. 3 and 4) travel preferably on circular rails *e*. The carriages for the airships, composed of several such trucks, and the airship thereon can thus be moved around within the shed, so that the airship can leave or enter in any direction. As shown in Figs. 3 and 4, the trucks *W* are preferably also fitted with hinged sides.

Right across the shed extends a fireproof partition wall *g*, which can swing around the king post *a* and divides the shed into two chambers, which are separated from each other in a fireproof manner. This partition travels on rollers *g*¹, which run on the circular rails *e*. The partition wall is composed of suitable posts and framework, the panels of which are filled with asbestos board or the like.

Airships which are to be suspended are preferably suspended from jibs *h* (see Fig. 2 on the right). These jibs are preferably made to swivel on pivots in the wall *g*, so that when not in use they can be turned flat to the wall. As the jibs *h* are secured to the wall *g* they and with them the airship suspended from them will travel with the wall *g*. Therefore, airships which are suspended, may be moved into departing position by turning the wall *g*. Of course the jibs may also be supported on independent posts or the like. And the entire floor of

the shed may be so arranged, that it can rotate within the shed and independently of the girders.

Fig. 5 illustrates the method of jointing the groups of girders or segments, composed of said girders, against each other. Between two such segments is placed a pneumatic tube p , which is thereupon inflated and will press tightly against the girders. This will not only provide an airtight joint between the several segments, but will also afford safety against explosions as in case of such explosion, the pneumatic tubes will fly out, and thereby relieve the girders and the shed of the force of the explosion. The several sectorlike sections of the shed may also be so arranged, that they can be coupled together and be simultaneously rotated around the axis of the shed, if and when this should be necessary or desirable. In this case the air ships, which are to be suspended, may be suspended from the girders, which compose the sections or sectors of the shed.

Another constructional form of the shed according to the present invention consists in the totality of the girders being coupled together into two groups, thus forming two half shells, of which the one has a somewhat larger diameter than the other, so that the one can pass beneath the other. In this case the shed need at the utmost be turned by one quarter of its circumference only for taking out the air ships. Furthermore the central tower structure may be dispensed with if the girders at the largest part of the shed sections are made sufficiently stronger. The shed section of the smaller diameter may be fitted with a stronger bracing at its widest part, on which bracing the shed section of the larger diameter is then fulcrumed. This constructional form is exemplified in Figs. 6 and 7. The shed here consists of the two semi-spherical shells b and c , fulcrumed on the central axis of the shed. The one shell b is made of such a diameter, that the other shell c can move under it. If the shells are made sufficiently strong the central tower a may also be dispensed with.

I claim:

1. A structure of the character described comprising spherical sections forming an inclosure and movable one within the other; and means for supporting said sections at the center thereof, substantially as described.

2. A structure for housing air-ships comprising spherical sections forming an inclosure and movable one within the other; and means for supporting an air-ship within the inclosure and moving the same to different positions therein, substantially as described.

3. A shed for airships and the like, said shed having a circular plan, a towerlike central structure, and composed of a plurality

of girders, combined to form sectors, said sectors rotating on the said central structure, and at the other end traveling on a circular foundation, the said sectors being of different diameters and adapted to be pushed, the one over the other while turning around the center of the shed as a fulcrum, thereby opening the shed.

4. A shed for airships and the like, said shed having a circular plan, a towerlike central structure, and composed of a plurality of girders, combined to form sectors, said sectors rotating on the said central structure, and at the other end traveling on a circular foundation, the said sectors being of different diameters and adapted to be pushed, the one over the other while turning around the center of the shed as a fulcrum, and comprising carriages for said airships, composed of several trucks and turntables secured on the latter, and adapted to be rotated around the axis of the shed.

5. A shed for airships and the like, said shed having a circular plan, a towerlike central structure, and composed of a plurality of girders, combined to form sectors, said sectors rotating on the said central structure, and at the other end traveling on a circular foundation, the said sectors being of different diameters and adapted to be pushed, the one over the other while turning around the center of the shed as a fulcrum, and comprising carriages for said airships, composed of several trucks, and turntables secured on the latter, and adapted to rotate around the axis of the shed, in said shed a partition, dividing the entire shed into two chambers separated from each other in an explosionproof manner, the said partition being movable and adapted to be rotated around the axis of the shed.

6. A shed for airships and the like, said shed having a circular plan, a towerlike central structure, and composed of a plurality of girders, combined to form sectors, said sectors rotating on the said central structure, and at the other end traveling on a circular foundation, the said sectors being of different diameters and adapted to be pushed, the one over the other while turning around the center of the shed as a fulcrum, and comprising carriages for said airships, composed of several trucks, and turntables secured on the latter, and adapted to be rotated around the axis of the shed, in said shed a partition, dividing the entire shed into two chambers separated from each other in an explosionproof manner, the said partition being movable and adapted to be rotated around the axis of the shed, on said partition jibs, from which airships can be suspended.

7. A shed for air ships and the like, said shed having a circular plan, a towerlike central structure and composed of a plurality

of girders, combined to form sectors, said sectors rotating on the said central structure, and at the other end traveling on a circular foundation, the said sectors being of 5 different diameters and adapted to be pushed, the one over the other while turning around the center of the shed as a fulcrum, the floor of the shed being rotatably fitted on rails and adapted to serve as car- 10 riage for the airships and also as bedplate for posts carrying jibs, on which airships may be suspended.

8. A shed for airships and the like, said shed having a circular plan, a towerlike central structure and composed of a plurality of girders, combined to form sectors, said sectors rotating on the said central structure, and at the other end traveling on a circular foundation, the said sectors being of 15 20 different diameters and adapted to be pushed, the one over the other while turning around the center of the shed as a fulcrum, all sectors of the said shed being arranged to be coupled with each other and 25 moved at one time the airships being sus-

pended from the girders, composing the shed.

9. A shed for airships and the like, said shed having a circular plan, a towerlike central structure and composed of a plurality of 30 girders, combined to form sectors, said sectors rotating on the said central structure and at the other end traveling on a circular foundation, the said sectors being of 35 different diameters and adapted to be pushed, the one over the other while turning around the center of the shed as a fulcrum, the sectors of the said shed being held in fixed relation to each other by means of pneumatic tubes placed between them at 40 points where they overlap.

In testimony, that I claim the foregoing as my invention, I have signed my name in presence of two witnesses, this 8th day of April 1913.

VINCENT WISNIEWSKI.
